DUCT STRUCTURE

William H. Goettl, 4627 N. Granite Reef Road,
Scottsdale, Ariz.
Filed Mar. 23, 1964, Ser. No. 353,842
8 Claims. (Cl. 138—37)

This invention relates to a duct structure and more particularly to a duct structure for use in air conditioning systems or the like wherein two flow passages are contained in a common duct and wherein these flow passages may be angularly displaced or rotated within the duct so that the relative disposition of the passages may communicate with any one of four sides of a duct as desired, thereby permitting the installation of equipment in connection with the ducts in such a manner as to switch the locations of the passages with respect to equipment coupled thereto.

This application discloses improvements upon the invention disclosed in my copending application for Duct Structure, Serial No. 281,841, filed May 20, 1963.

In the installation of air conditioning ducts it has been a problem, for example, to provide a common duct having two flow passages for the delivery of refrigerated air from a refrigeration unit and for the return of room air thereto; said problem most commonly existing in the mechanical disposition of the refrigeration unit with respect to the ducting so that the delivery and return air duct sections of a refrigeration unit coincident with the passages in the air conditioning duct and yet permit convenient installation of the refrigeration unit.

In many instances where ducts are used for air conditioning purposes they contain two parallel passages and oftentimes these passages extend through walls or between walls and it is desired to provide for return air and air delivery grills in various horizontal or vertical orientation in order to accommodate the physical features of a building structure.

Various roof mounted refrigeration systems have been used for air conditioning and these systems include cool air delivery duct sections as well as return sections which are normally coupled to a common duct having separate flow passages, these flow passages are appropriately connected to grills for the delivery of cold air into a room and for the return of air to the refrigeration unit. After the ducts have been installed in the building, the refrigeration unit may subsequently be installed, but it may be found that due to interference with the roof top or some other feature of the building the air conditioning unit cannot be installed on the duct conveniently so that the duct passages coincide to permit the return air duct section to communicate properly with the return duct section of the unit and to permit the cool air delivery duct section to communicate with the cold air delivery section of the refrigeration unit.

Accordingly, it is an object of the present invention to provide a duct structure which is particularly adapted for use in buildings and in connection with air conditioning systems therein for the purpose of conveniently orienting inlet and outlet grills in adjacent rooms having different angularly disposed air delivery and return axes.

Another object of the invention is to provide a duct structure having substantially rectangular cross section and provided with separate duct sections separated by baffle structures which are disposed angularly to twist the duct passage either 90 or 180 degrees so that the relative disposition of two duct passages in the duct structure may be changed 90 degrees or 180 degrees as desired.

Another object of the invention is to provide a very simple duct and baffle structure wherein a single sheet of metal separates two flow passage portions in the duct

2

section and wherein said single sheet baffle section is formed into two integral portions, one of which is a triangle and another of which is trapezoidal and whereby two of the single sheets, each having a triangular and trapezoidal portion, are connected together to form a baffle structure which turns 90 degrees within said duct section.

Another object of the invention is to provide a novel duct structure which is substantially rectangular in cross section and wherein a novel baffle structure extends across the interior of the duct from side to side to provide two duct flow passages and wherein the baffle structure comprises a pair of sheet metal plates connected together to form a 90 degree rotational turn of the separate flow passages in the duct, each of said plates having a triangular portion extending from side to side across the interior of the duct and each plate also having an integral trapezoidal portion disposed at a compound angle with respect to the cross section of the duct, thereby providing a very simple means for turning a pair of flow passages in a duct and which structure may readily be made on a conventional sheet metal brake.

Another object of the invention is to provide a novel duct structure composed of a plurality of duct sections and angular baffles therein, said duct sections coupled together in a unitary structure and readily insertably in a conventional duo passage duct system for exchanging the horizontal or vertical disposition of rectangular in cross section passages in the duct or for switching these passages rotationally 180 degrees, as desired, for the purpose of accommodating the desired locations of equipment disposed at opposite end of an air conditioning duct.

Further objects and advantages of the invention may be apparent from the following specification, appended claims and accompanying drawings, in which:

FIG. 1 is an end perspective view of a duct structure in accordance with the present invention and showing fragmentarily a duplicate structure in connection therewith;

FIG. 2 is a view similar to FIG. 1, showing angular baffle structure of the duct structure disclosed in FIG. 1 and showing in phantom by broken lines the outside duct section structure of the invention;

FIG. 3 is an end view of the duct structure of the invention;

FIG. 4 is a sectional view taken from the line 4—4 of FIG. 3, showing the baffle structure of the invention;

FIG. 5 is an exploded view taken from the line 5—5 of FIG. 4, showing the one piece baffle members, disclosed in FIG. 4, separated to amplify the illustration;

FIG. 6 is a view of the exploded baffle structures taken from the line 6—6 of FIG. 5;

FIG. 7 is a view of a flat blank from which one of the baffle structures of the invention is formed;

FIG. 8 is an enlarged fragmentary sectional view taken from the line 8—8 of FIG. 1;

FIG. 9 is an enlarged fragmentary sectional view taken from the line 9—9 of FIGS. 1 and 2 of the drawings;

FIG. 10 is a fragmentary view of a building structure showing a duct structure of the present invention installed therein and illustrating the duct structure connected to an air conditioner and showing by broken lines the facility of moving the air conditioner around 180 degrees with relation to the axis of the duct structure in accordance with the convenience of the twisted passage structure of the present invention;

FIG. 11 is a fragmentary sectional view of a building structure showing a dual passage air conditioning duct installed horizontally therein and wherein the dual passages are separated by an intermediate vertically disposed baffle;

FIG. 12 is another view similar to FIG. 11, but showing a dual passage duct structure having a horizontally disposed baffle separating a pair of duct passages in the duct, thereby illustrating the possibility of axial rotation of the passage structures substantially 90 degrees from the disclosure of FIG. 11 to the disclosure of FIG. 12, in accordance with the invention;

FIG. 13 is a view of a pair of the baffle plates of the invention taken from the line 13—13 of FIG. 2;

FIG. 14 is an enlarged fragmentary sectional view taken from line 14—14 of FIG. 13; and

FIG. 15 is an enlarged fragmentary sectional view taken from line 15—15 of FIG. 13.

As shown in FIGS. 1 and 2 of the drawings, the duct structure of the present invention includes a duct section 20 which is substantially rectangular in cross section having normally upper and lower sides 22 and 24, respectively, which are substantially parallel with each other and a pair of substantially vertical sides connected therewith designated 26 and 28, respectively, all of which form a rectangular in cross sectional duct structure.

As shown in FIG. 7 of the drawings, baffle sections are disposed in each duct section 20 and these baffle sections, as shown in FIG. 7, are made of a single piece of sheet metal designated 30. This metal is broken at breaklines 32, 34, 36, 38 and 40 to outline one triangular section 42 and one trapezoidal section 44.

Adjacent the break lines 36, 38 and 40 are flanges 46, 48 and 50, respectively, which are disposed to connect the baffle structure with the inner walls of the duct sides 22, 24, 26 and 28 and with respective edge portions 52 of adjacent triangular sections 42.

Adjacent the break line 32 is a flange 54 which is adapted to interconnect passages dividing baffles of adjacent duct sections 20 which are axially connected together, as shown in FIG. 1 of the drawings, and which will be hereinafter described in detail.

As shown in FIG. 1 of the drawings, a baffle structure separates the duct 20 into two separate flow passages 56 and 58 which are disposed on opposite sides of one of the triangular portions 42 of the baffle structure. These triangular portions 42 extend across the duct structure and have planes which are substantially parallel to opposite sides of the rectangular in cross section duct structure.

Connected to an edge 52 of one of the duct sections is a complementary flange 46 of one of the trapezoidal sections, as will be hereinafter described, all of which forms a 90 degree rotational transition of the baffle structure in the duct 20. The flange 46 of one of the trapezoidal sections is spot welded to the respective edge 52 of the triangular section 42, all as shown best in FIG. 1 of the drawings.

This may also be clear from an inspection of FIG. 2 of the drawings, wherein the duct structure is broken away to expose the baffles internally thereof. As shown in FIG. 2 of the drawings, it will be seen that the flange 50 of the trapezoidal section 44 is connected to the top 22 of the duct structure by means of spot welds 60 and that the flange 48 of the baffle section 30 at another edge of the trapezoidal portion 44 is connected by spot welds 62 to the side 26 of the duct 20, shown in FIGS. 1 and 2 of the drawings.

It will be seen that the disclosure of FIG. 3 shows an opposite end of the duct and baffle structure from that shown in FIG. 2. Thus, FIG. 3 discloses the structure as viewed in a direction of the arrow A in FIG. 2 of the drawings, wherein one triangular section 42 of one of the baffle members is disposed horizontally. Thus, the triangular section 42, shown in FIG. 3, is disposed 90 degrees from the triangular section 42, most plainly shown in FIG. 2 of the drawings.

Accordingly the duct passages 56 and 58 are rotated 90 degrees from the disclosure of FIGS. 1 and 2 to the

disclosure of FIG. 3. As for example, the duct passage 56 at one end of the duct 20 is disclosed adjacent the wall 28 and at the opposite end of the duct 20, as shown in FIG. 3, the duct passage 56 is adjacent the wall 22.

5 Likewise, the duct passage 58, shown in FIG. 1 of the drawings, adjacent the wall 26 is disposed at the opposite end of the duct section 20 adjacent the lower wall 24 of the baffle sections 30 are disposed to divide the flow passage sections and extend at 90 degrees to opposite sides of the duct section 20 while the trapezoidal sections 44 extend at compound angles with respect to lateral and longitudinal axes of the duct 20.

As shown in FIG. 4 of the drawings, spot welds 66 connect a respective edge 52 of one of the triangular baffle sections with a respective flange 46 of a trapezoidal section 44.

As shown in FIGS. 5 and 6 of the drawings, due to the direction in which the views are taken, the exploded 20 view of the baffle plates 30 is such as to disclose them substantially upside down, as shown in FIG. 1 of the drawings, but arranged in an axial end view similar to that shown in FIG. 3.

It will be seen that each baffle section, as shown in 25 FIG. 7, includes a triangular section 52 and a trapezoidal section 44, each trapezoidal section 44 at its flanges 46 is spot welded to a complementary edge portion 52 of each triangular section 42 by means of spot welds 66, thus, each 90 degree section involving a pair of the baffle plates 30 includes a connection of each flange 46 of each trapezoidal section 44 with a complementary edge 52 of a triangular section 42. Thus, there are two flanges 46 and two edges 52 which are connected together by spot welds 60 and each baffle section 30, thus, contributes substantially 35 45 degrees to the turning of the structure whereby two of the baffle sections 30, thus, connected as shown herein provides a baffle structure which turns the passage sections 56 and 58 in the duct 20 substantially 90 degrees.

It will be seen from a disclosure of FIGS. 13, 14 and 40 15 that the flange portions 46 of each trapezoidal section 44 of each baffle section 30 extend into connection with a respective edge 52 of each of the triangular portions 44 and in the assembly of two of these baffle sections 30, as shown in FIG. 13, the triangular flanges 46 extend 45 in opposite directions to each other and their respective break lines 36 are disposed almost in alignment with each other and, also, that the edge portions 52 of the triangular portions 42 are almost in alignment with each other.

50 Each duct section 20 at the ends of its sides 26 and 28 is provided a hook flange portion 70, shown best in FIGS. 1 and 4 of the drawings. Each hook portion 70 of adjacent duct walls 26 is opposed to the adjacent hook portion 70 so that a channel shaped clip 72 may be slidably 55 engaged thereover to hold the respective adjacent duct sections 20 together. Accordingly, it will be appreciated that the baffle structure in each duct section 20 may rotate the flow passages 56 and 58, 90 degrees so that two of the duct sections 20 connected end to end will rotate 60 the flow passages 100, 180 degrees.

The upper and lower walls 22 and 24 of the duct 20 are connected by an S-shaped clip 74 which embraces overlapping edges 76 of these walls 22 and 24. Thus, the duct sections 20 are held together in end to end communicative relationship with each other. It will also be noted that the end flanges 54 of the triangular baffle sections 42 are also connected by an S-shaped clip 74, as indicated by the section line 99 in FIG. 2, whereas the section line 99 of FIG. 1, indicates the same S-shaped 65 clip structure 74 for connecting a pair of the outer opposed walls 22 and 24 of adjacent duct sections 20.

As shown in FIG. 10 of the drawings, an air conditioner 82 may conveniently be installed in a solid line position, as shown, rather than in a broken line position 70 75 88 which would normally interfere with the gable 90 of

the building roof. The duct sections 20 installed in connection with the inlet 86 and outlet 84 of the air conditioner 82 permit the air conditioner 82 to be installed in the solid line position and, thus, the duct passages 56 and 58 are rotated substantially 180 degrees from their position in the wall 80, all as shown in FIG. 10 of the drawings. This facility, thus, permits a low mounting of the air conditioner 82 and permits it to be installed so that it doesn't interfere with the gable 90 in accordance with preinstalled duct structures having the passages 56 and 58 oriented in the wall 80, as shown. This situation occurs in many instances and in such instances the basic duct work has already been installed in the home before the customer decides what type of air conditioner he needs and what its configuration will be. When the some is sold, the final installation takes place and it is oftentimes necessary to rotate the passages in order to afford the convenience in the unobstructed installation of the air conditioner, all as illustrated in FIG. 10 of the drawings.

The passages 56 and 58 installed in a wall section 80, as shown in FIG. 11 of the drawings, may be rotated substantially 90 degrees to a position, as shown in FIG. 11 of the drawings, to provide for convenience of inlet and outlet grills on opposite sides of the wall structure 80. Accordingly, one duct section 20, in accordance with the present invention, may be utilized to rotate the passages 56 and 58 from the position, as shown in FIG. 11, to the position, as shown in FIG. 12, thus, the 90 degree rotation affords the possibility of opposed inlets and outlets on opposite sides of the wall 80 communicating with both of the passages 56 and 58.

It will be obvious to those skilled in the art that various modifications of the present invention may be resorted to in a manner limited only by a just interpretation of the following claims.

I claim:

1. In a dual passage duct structure the combination of: a rectangular in cross section hollow duct structure having four sides and having two passages therein; a baffle separating said passages; first and second sheet metal baffle plates of said baffle; each of said baffle plates comprising a triangular section and a trapezoidal section; an edge of each trapezoidal section connected to an edge of each triangular section of each baffle plate; each trapezoidal section disposed at an angle to each triangular section of each baffle plate whereby said edge of each trapezoidal section is connected to a respective edge of each triangular section to provide a 90 degree twist in the baffle structure formed by the two plates; each triangular section being disposed at right angles to two opposite sides of said rectangular in cross section duct structure; one of said triangular portions of one of said plates being disposed at 90 degrees to a respective triangular portion of the other baffle plate.

2. In a dual passage duct structure the combination of: a rectangular in cross section hollow duct structure having four sides and having two passages therein; a baffle separating said passages; first and second sheet metal baffle plates of said baffle; each of said baffle plates comprising a triangular section and a trapezoidal section; an edge of each trapezoidal section connected to an edge of each triangular section of each baffle plate; each trapezoidal section disposed at an angle to each triangular section of each baffle plate whereby said edge of each trapezoidal section is connected to a respective edge of each triangular section to provide a 90 degree twist in the baffle structure formed by the two plates; each triangular section being disposed at right angles to two opposite sides of said rectangular in cross section duct structure; one of said triangular portions of one of said plates being disposed at 90 degrees to a respective triangular portion of the other baffle plate; a second edge portion of each trapezoidal section being connected to a side wall of said

duct structure disposed in a plane 90 degrees to the triangular section of the respective baffle plate.

3. In a dual passage duct structure the combination of: a rectangular in cross section hollow duct structure having four sides and having two passages therein; a baffle separating said passages; first and second sheet metal baffle plates of said baffle; each of said baffle plates comprising a triangular section and a trapezoidal section; an edge of each trapezoidal section connected to an edge of each triangular section of each baffle plate; each trapezoidal section disposed at an angle to each triangular section of each baffle plate whereby said edge of each trapezoidal section is connected to a respective edge of each triangular section to provide a 90 degree twist in the baffle structure formed by the two plates; each triangular section being disposed at right angles to two opposite sides of said rectangular in cross section duct structure; one of said triangular portions of one of said plates being disposed at 90 degrees to a respective triangular portion of the other baffle plate; a second edge portion of each trapezoidal section being connected to a side wall of said duct structure disposed in a plane 90 degrees to the triangular section of the respective baffle plate; a third edge portion of said trapezoidal section secured to a wall of said duct structure disposed parallel to the triangular portion of the respective baffle plate.

4. In a dual passage duct structure the combination of: a rectangular in cross section hollow duct structure having four sides and having two passages therein; a baffle separating said passages; first and second sheet metal baffle plates of said baffle; each of said baffle plates comprising a triangular section and a trapezoidal section; an edge of each trapezoidal section connected to an edge of each triangular section of each baffle plate; each trapezoidal section disposed at an angle to each triangular section of each baffle plate whereby said edge of each trapezoidal section is connected to a respective edge of each triangular section to provide a 90 degree twist in the baffle structure formed by the two plates; each triangular section being disposed at right angles to two opposite sides of said rectangular in cross section duct structure; one of said triangular portions of one of said plates being disposed at 90 degrees to a respective triangular portion of the other baffle plate; a second edge portion of each trapezoidal section being connected to a side wall of said duct structure disposed in a plane 90 degrees to the triangular section of the respective baffle plate; a third edge portion of said trapezoidal section secured to a wall of said duct structure disposed parallel to the triangular portion of the respective baffle plate; one edge of said triangular portion extending outwardly and disposed from one side of said duct structure to an opposite side thereof and separating the duct cross section into two flow passages at one end thereof.

5. In a dual passage duct structure the combination of: a rectangular in cross section hollow duct structure having four sides and having two passages therein; a baffle separating said passages; first and second sheet metal baffle plates of said baffle; each of said baffle plates comprising a triangular section and a trapezoidal section; an edge of each trapezoidal section connected to an edge of each triangular section of each baffle plate; each trapezoidal section disposed at an angle to each triangular section of each baffle plate whereby said edge of each trapezoidal section is connected to a respective edge of each triangular section to provide a 90 degree twist in the baffle structure formed by the two plates; each triangular section being disposed at right angles to two opposite sides of said rectangular in cross section duct structure; one of said triangular portions of one of said plates being disposed at 90 degrees to a respective triangular portion of the other baffle plate; a second edge portion of each trapezoidal section being connected to a side wall of said duct structure disposed in a plane 90 degrees to the triangular section of the respective baffle plate; a third edge portion of said trapezoidal section secured to a wall of said duct

structure disposed parallel to the triangular portion of the respective baffle plate; one edge of said triangular portion extending outwardly and disposed from one side of said duct structure to an opposite side thereof and separating the duct cross section into two flow passages at one end thereof; a pair of said rectangular in cross section hollow duct structures connected end to end to each other; and means interconnecting the last mentioned edges of adjacent triangular sections of said baffle structures.

6. In a dual passage duct structure the combination of: a rectangular in cross section hollow duct structure having four sides and having two passages therein; a baffle separating said passages; first and second sheet metal baffle plates of said baffle; each of said baffle plates comprising a triangular section and a trapezoidal section; an edge of each trapezoidal section connected to an edge of each triangular section of each baffle plate; each trapezoidal section disposed at an angle to each triangular section of each baffle plate whereby said edge of each trapezoidal section is connected to a respective edge of each triangular section to provide a 90 degree twist in the baffle structure formed by the two plates; each triangular section being disposed at right angles to two opposite sides of said rectangular in cross section duct structure; one of said triangular portions of one of said plates being disposed at 90 degrees to a respective triangular portion of the other baffle plate; a second edge portion of each trapezoidal section being connected to a side wall of said duct structure disposed in a plane 90 degrees to the triangular section of the respective baffle plate; a third edge portion of said trapezoidal section secured to a wall of said duct structure disposed parallel to the triangular portion of the respective baffle plate; one edge of said triangular portion extending outwardly and disposed from one side of said duct structure to an opposite side thereof and separating the duct cross section into two flow passages at one end thereof; a pair of said rectangular in cross section hollow duct structures connected end to end to each other; and means interconnecting the last mentioned edges of adjacent triangular sections of said baffle structures; adjacent ends of said duct structures having hook shaped flanges; and channel structures having opposed portions engaging said hook shaped flanges for holding said duct structures in end to end connected relationship to each other.

7. In a dual passage duct structure the combination of: a rectangular in cross section hollow duct structure having four sides and having two substantially rectangular flow passages therein; a baffle separating said passages; first and second sheet metal baffle plates of said baffle, each of said plates having integral triangular and trapezoidal portions broken at an angle to each other; one edge of said triangular portion of each plate extending across said hollow

duct structure from one side to the other thereof and dividing the cross section of the duct into said two passages; each trapezoidal portion of each of said plates disposed at an angle to the sides of said duct structure; a first edge of each trapezoidal section secured to one edge of each respective triangular portion of each of said plates; said edges of two connected plates extending in substantially opposite directions and in substantial alignment with each other at their breaks with the respective trapezoidal sections whereby two triangular sections of said plates and their respective trapezoidal sections when connected together create a substantially 90 degree rotational baffle structure in said duct structure whereby one of said triangular portions is disposed at 90 degrees to a triangular portion of the respective second baffle plate so that one of said triangular portions extends across said duct structure normal to one pair of said sides and the other triangular portion extends across said duct structure at 90 degrees thereto and normal to the two remaining sides disposed at 90 degrees to the first mentioned pair of sides.

8. In a dual passage duct structure the combination of: a rectangular in cross section hollow duct structure having four sides and having two passages therein; a baffle separating said passages; first and second sheet metal baffle plates of said baffle; each of said baffle plates comprising a triangular section and a trapezoidal section; an edge of each trapezoidal section connected to an edge of each triangular section of each baffle plate; each trapezoidal section disposed at an angle to each triangular section of each baffle plate whereby said edge of each trapezoidal section is connected to a respective edge of each triangular section to provide a 90 degree twist in the baffle structure formed by the two plates; each triangular section being disposed at right angles to two opposite sides of said rectangular in cross section duct structure; one of said triangular portions of one of said plates being disposed at 90 degrees to a respective triangular portion of the other baffle plate; flange portions of one of said plates disposed in overlapped connected relation to the other of said plates at adjacent edges of said triangular and trapezoidal sections.
